United States Patent

Des. 238,722

Patented Feb. 3, 1976

238,722

COFFEE MAKER

Stewart L. Black, Lee's Summit, Mo., assignor to
The Vendo Company, Kansas City, Mo.

Filed Oct. 21, 1974, Ser. No. 516,434

Term of patent 14 years

Int. Cl. D7—02; D15—08

U.S. Cl. D94—3 B

Fig. 1.

Fig. 2.

Fig.3.

Fig.5.

Fig.4.

FIG. 1 is a perspective view of a coffeemaker showing my new design from the front, top, and one side thereof;

FIG. 2 is a side elevational view of the opposite side thereof;

FIG. 3 is a top plan view thereof;

FIG. 4 is a front elevational view thereof; and

FIG. 5 is a rear elevational view thereof.

I claim:

The ornamental design for a coffeemaker, as shown.
